DESIGN FOR A DESK TOOL

Frank J. Becker, Independence, Mo.

Application March 12, 1934, Serial No. 51,018

Term of patent 14 years

To all whom it may concern:

Be it known that I, FRANK J. BECKER, a citizen of the United States, residing at Independence, in the county of Jackson and State of Missouri, have invented a new, original, and ornamental Design for a Desk Tool, of which the following is a specification, reference being had to the accompanying drawing, forming a part thereof.

Figure 1 is a perspective view of the desk tool.
Fig. 2 is a side elevation of the same, and
Fig. 3 is an edge elevation of the desk tool.
I claim:

The ornamental design for a desk tool, as shown.

FRANK J. BECKER.
